LADY'S COSTUME.

No. 18,023.

Patented Jan. 24, 1888.

UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,023, dated January 24, 1888.

Application filed December 9, 1887. Serial No. 257,465. Term of patent 3½ years.

To all whom it may concern:

Be it known that I, HENRIETTA F. DUKE, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a round walking-skirt and a close-fitting basque. The skirt displays a kilt-plaited panel on the left-side gore, a long front drapery that exhibits a broad revers down its left-side edge, which falls nearly to the edge of the skirt, and plaits in its top and also in its right-side edge, the lower outline being curved, and a full back drapery that falls nearly to the edge at the left side, curves shorter at the right side, where it displays a group of plaits near the lower edge, and exhibits two long bournous loops falling over plaits and loopings. The basque extends but a short distance below the waist-line, and displays fronts folding back in revers all the way down over a slightly-longer vest that is pointed at the closing, a back that is slightly pointed at the center, a standing collar, and coat-sleeves.

What I claim as my invention, and desire to secure by Letters Patent, is—

The design for a lady's costume, as shown in the engraved prints accompanying this specification.

HENRIETTA F. DUKE.
